UNITED STATES PATENT OFFICE

WILLIAM F. HOGAN, OF WILDWOOD, NEW JERSEY

FLAG HOLDER FOR ELECTRIC-LIGHT POLES

Application filed May 14, 1929. Serial No. 363,001.

This invention relates to certain novelties used in the decorating of lamp posts, particularly electric light poles.

The leading object of the present invention may be said to provide a novel arrangement, combination, and connection of parts in which both flags and pennants or streamers may be used for decorative purposes upon the lamp post.

10 A further object is to provide a metal structure which is relatively light and which may be stamped out of sheet metal, thus providing a very simple, neat appearing, and inexpensive arrangement of parts.

15 A further object of the present invention is to provide a device of the character under consideration which may be adjustably attached to electric light poles and which may be readily taken down or left upon the posts 20 as desired.

A still further object of the present invention is to provide a structure in such manner that the flag staffs may be readily inserted and removed by very simple attachment means while the supports are in position upon the lamp posts.

Other and further objects not at this time appearing will be hereinafter set forth.

The invention consists of the novel construction hereinafter described and finally claimed.

The nature, characteristic features and scope of the invention will be more fully understood from the following description 35 taken in connection with the accompanying drawings forming part hereof, and in which:

Fig. 1, is a fragmentary view in elevation of a lamp post equipped with the flag holder 40 of the invention.

Fig. 2, is a top or plan view of Fig. 1.

Fig. 3, is a top or plan view of one of the sections for holding the flag staff.

Fig. 4, is a view of the underside of Fig. 3.

Fig. 5, is a view in cross section taken upon the line 5—5 of Fig. 3.

Fig. 6, is a fragmentary view in cross section of one of the pennant holding members.

50 Fig. 7, is a view in perspective of one of

the pennants shown in Fig. 1 in folded form for shipping purposes.

Fig. 8, is a fragmentary view in plan showing a modified structure for supporting a flag staff.

Fig. 9, shows in cross section the parts shown in Fig. 8, Fig. 9, however, showing one of the flag staffs in dotted lines.

Fig. 10, is a top or plan view, partly sectioned, showing a modified form of lamp post 60 clamp.

Fig. 11, is a view in elevation of one of the sections shown in Fig. 10.

Fig. 12, is a fragmentary view in section illustrating how halyards may be employed 65 for raising pennants to the cross arms.

For the purpose of illustrating my invention I have shown in the accompanying drawings several forms thereof which are at present preferred by me, since the same have been 70 found in practice to give satisfactory and reliable results, although it is to be understood that the various instrumentalities of which my invention consists can be variously arranged and organized and that my invention 75 is not limited to the precise arrangement and organization of the instrumentalities as herein shown and described.

Referring to the drawings, the reference numeral 1 designates the post which may be 80 a lamp post, a pole for supporting electric wires, or any other type of pole which are usually cylindrical. Arranged to be clamped around the pole 1 is a plurality of arms 2 for supporting the flag staffs 3. The arms 2, of 85 which three are shown in the drawings, carry at their inner ends semi-circular plates 4, which are arranged to be clamped around a post 1 by means of bolts 5. This is very clearly seen in Fig. 2. The plates 4 are provided with flanges 6 for accommodating the bolts 5. The plates 4 and flanges 6 are arranged in a perpendicular manner whereas the flag staff arms are arranged at an inclination. The outer ends of the flag staff arms 2 90 each carries a cross arm for supporting a pennant or the like.

Referring now more particularly to Figs. 3, 4, and 5, the arms 2 in cross section are substantially V-shaped and are provided with 100

inturned ends 8 which engage the semi-circular plate 4, see Fig. 5, and the upper and lower rims of the plate 4 are outwardly flanged as at 9, and the flag staff arms 2 are so arranged that their flanges 8 abut against the flanges 9 of the plate 4. This provides a very light but rigid structure which is desirable in case of high winds. The outer end of each flag staff arm 2 is apertured horizontally to receive a bolt 10, the outer end of which is provided with a butterfly nut 11 and the inner end of which is provided with an eye 12. In use the flag staff 3 is introduced through an aperture 13, down through the eye 12, and through a slot 14 in the arm, and the bolt is then tightened, thus rigidly locking the flag staff to place and which result is accomplished very easily.

Taking up now more particularly the structure shown in Fig. 6, the cross arm 7 for supporting the pennant or the like 15 is also of V-shaped cross section and is apertured upon its horizontal extension 16 for the passage therethrough of a bolt 17 for securing the pennant or the like to place. The lower or angular extension of the part 7 conceals the nut 18 from the view of passersby. The outer end of each cross arm 7 is slotted as at 19 so that a halyard 20, to which is attached a pennant, may be employed. This is useful in running up pennants to the cross arms and then securing the halyards to the post itself.

In lieu of the flag staff securing arrangement shown in Fig. 5, I may provide in the arm 2 an aperture 21 provided with prongs 22. In using the flag staff the same is forced through aperture 21 and through the slot 14 and the staff then slightly moves about its vertical axis so that the prongs 22 engage the wood of the flag staff and securely holds the flag in place. This provides a very simple means of securing the flags in desired position. This construction is seen in Figs. 8 and 9.

It is sometimes desirable to adjust the device around the lamp post or other pole, and to this end I provide the construction shown in Figs. 10 and 11. In this case each flag staff supporting arm 2 is provided with a semi-circular plate 23, which plates overlap one another. These plates 23 are each apertured as at 24 so that bolts 25 may be used to adjust these plates with respect to one another, as clearly seen in Fig. 11. The apertures 24 are arranged at an inclination with respect to the plates. Thus, adjustment may be made to take care of poles of varying diameters.

I am aware that the invention may be embodied in other specific forms without departing from the spirit or essential attributes thereof, and I therefore desire the present embodiment to be considered in all respects as illustrative and not restrictive, reference being had to the appended claims rather than

to the foregoing description to indicate the scope of the invention.

Having thus described my invention, what I claim as new and desire to secure by Letters Patent, is:

1. In a device of the character stated, means to be clamped around a pole, a flag staff supporting arm extended from said means, said arm being of thin metal and of V-shaped cross section and having inturned vertically disposed ends, means for supporting said flag staff with respect to said arm, and a horizontally arranged cross arm carried by said staff supporting arm at right angles thereto to support a pennant.

2. In a device of the character stated, means to be clamped around a pole, a flag staff supporting arm extended from said means, said arm being of thin metal and of V-shaped cross section, means for supporting said flag staff with respect to said arm, and a horizontally disposed cross arm carried by said staff supporting arm for supporting a pennant, said cross-arm being of V-shaped cross-section.

WILLIAM F. HOGAN.
